WILLIAM C. STEVENS AND ARTHUR SIMON, OF MILWAUKEE, WISCONSIN, ASSIGNORS
TO THE CUTLER-HAMMER MFG. CO., OF MILWAUKEE, WISCONSIN, A CORPORATION
OF WISCONSIN.

ALTERNATING-CURRENT ELECTROMAGNETICALLY-OPERATED DEVICE.

Original application filed July 24, 1916, Serial No. 110,945. Divided and this application filed June 20, 1923. Serial No. 646,513.

This invention relates to devices operable by alternating current electromagnets and is particularly applicable to alternating current switches of the clapper type.

- 5 In such a switch, as in various other devices, the attracted element requires a considerably greater operating force as it approaches its limit of movement than is required for the initial and sometimes the major part of its movement. On the other hand, an alternating current magnet inherently tends to produce a substantially constant magnetic flux for a given voltage impressed thereon and in consequence if it 10 be designed of sufficient strength to actuate and hold a clapper switch or the like it inherently tends to actuate the same with a very objectionable slam due to the disproportion of its magnetic flux and initial load.
- 20 The present invention has for an object to curtail the slamming tendency of such devices.

A further object is to provide for graduation of the magnetic pull exerted upon the 25 attracted element according to its position.

Other objects and advantages of the invention will hereinafter appear.

This application is a division of our application filed July 24, 1916, Serial No. 30 110,945.

The accompanying drawing illustrates an embodiment of the invention which will now be described, it being understood that the same is susceptible of various modifications 35 without departing from the scope of the appended claims.

In the drawing,

Figure 1 is a front elevation of a clapper switch constituting an embodiment of the 40 invention; and Figure 2 is a side elevation of the electromagnet employed to operate the switch.

The switch illustrated in the drawing is of the double pole type and comprises stationary contacts 1, co-operating movable contacts 2, a magnet frame 3 having an alternating current winding 4 mounted thereon and held in place by members 4^a attached to frame 3 in the manner indicated at 4^b. Lever 5 is mounted on said frame to carry 50 said movable contacts and has a part 6 constituting an armature for said winding, all

of said parts being mounted upon a suitable panel 7. The contacts 2 are pivotally mounted upon brackets 8 fixed to the lever 5 and 55 are provided with tension springs 9 against which the electromagnet must pull after initial engagement of said contacts 2 with the contacts 1. Thus during the movement of the lever from normal position to its position representing initial engagement of the co-operating contacts, the load upon the electromagnet is very much lighter than during the continued movement of the lever 60 against the action of spring 9 and yet the 65 electromagnet must be sufficiently strong to forcibly engage the contacts and hold the springs under tension for continued firm engagement of said contacts.

The magnet frame which comprises laminations assembled upon a rigid support 10, has an extended upper pole 3^a and a short lower pole 3^b. The winding 4 is mounted upon the pole 3^b and, slightly in advance of the outer end of said winding, said pole is 70 provided with a perpendicular polar face 3^c 75 constituting an abutment for the armature 6. The armature 6 is also formed of laminations supported by an extension 5^a of the lever 5 in such a manner as to provide for movement of said armature beneath the extended pole 3^a of the magnet frame, said lever 80 being pivotally supported for such movement upon a spindle 11 carried by the support 10. The upper extremity of the armature 6 and the adjacent face of the extended pole 3^a are curved concentrically with the 85 pivot of the lever and accordingly the clearance between said parts will remain constant throughout the movement of the armature, said clearance being relatively small 90 as compared with the maximum distance between the armature and polar face 3^c. Further, the pole 3^a is provided with a plurality of conducting bands or closed coils 12, similar to shading coils, arranged thereon in planes substantially perpendicular to the path of the flux through said pole. The face of the pole adjacent to the end of the armature is slotted to permit said coils to be 95 inset therefrom and said coils are so positioned 100 as to lie across the path of the magnetic flux in biased position of the armature and to be shunted progressively by the magnetic flux

as the armature advances in attracted direction.

Thus with the armature in biased position, as indicated by dotted lines, and with the winding energized the magnetic flux passing through the extended pole 3^a will induce current in all of the coils 12 with the result of producing a magnetic flux opposing the main flux. Such opposing flux will tend to divert the main flux from its path through the armature and cause the latter flux to pass directly to pole 3^b across the air gap between the two poles with a resulting curtailment of the magnetic pull exerted upon the armature and accordingly upon the contact carrying lever. A part of the main flux will, however, pass to and through the armature and thence to the pole 3^b, or vice versa, with the result of attracting the armature and lever and as the armature advances it will progressively exclude the coils 12 from the path of the main flux thereby decreasing the opposing flux and increasing the amount of flux passing to the armature with a consequent increase in pull upon said armature. When the armature finally abuts the pole 3^b it will exclude the coils 12 from the magnetic circuit of the electromagnet and in consequence said armature will be subjected to the full attractive force of the electromagnet for engagement of the contacts and retention thereof in engaging relation.

The curtailment and graduation of the magnetic pull upon the armature is dependent upon the number and arrangement of coils 12 and as will be apparent, by varying the number and arrangement of said coils different pull curves may be obtained.

What we claim as new and desire to secure by Letters Patent is:—

1. The combination with a device to be operated, of an alternating current electromagnet having a magnetic frame, an armature movable with reference to said frame for operating said device and means on said frame to oppose the passage of the effective magnetic flux to said armature when in initial position to thereby curtail the magnetic pull exerted upon said armature in such position.

2. The combination with a device to be operated, of an alternating current electromagnet having an armature for operating the same and having a winding about a pole thereof to provide a magnetic flux opposing the magnetic flux to said armature to thereby curtail the pull exerted thereon, said winding being effective only during an initial part of the movement of said armature.

3. The combination with a device to be operated, of an alternating current electromagnet having a magnetic frame, an armature pivotally supported by said frame for operating said device and means carried

by said frame to initially curtail the effective magnetic flux through said armature to thereby reduce the initial magnetic pull upon said armature.

4. The combination with a device to be operated, of an alternating current electromagnet having a magnetic frame, an armature pivotally moved with respect to said frame for operating said device and means fixed to said frame to oppose the passage of the effective magnetic flux to said armature to thereby curtail the initial magnetic pull exerted upon said armature.

5. The combination with a device to be operated, of an alternating current electromagnet having an armature for operating said device and means to oppose the passage of its magnetic flux to said armature when in initial position to thereby curtail the magnetic pull exerted upon said armature in such position, said means including a pole having a plurality of closed coils thereon and a surface in uniformly spaced relation to said armature during the entire movement of the latter.

6. The combination with a device to be operated, of an alternating current electromagnet, a pivoted armature for operating said device having a terminal portion adjacent one pole of said electromagnet the adjacent faces of said pole and armature being curved concentrically with respect to said pivot, said pole having slots and conducting bands in said slots arranged to direct a portion of the magnetic flux across the air gap between said pole and the other pole of the electromagnet to thereby curtail the initial pull exerted upon said armature.

7. The combination with an alternating current electromagnet having a long pole and a short pole, an armature movable toward and away from said short pole in uniformly spaced relation to said long pole, and means on said long pole to oppose the passage of the magnetic flux to said armature, to thereby curtail the magnetic pull exerted upon said armature by said short pole when in initial position.

8. The combination with a device to be operated, of operating means therefor comprising an alternating current electromagnet having relatively movable parts, and means comprising a conductive coil so associated with the electromagnet as to provide for shunting progressively different values of the magnetic flux during relative movement of said parts.

9. The combination with a device to be operated, of operating means therefor comprising an alternating current electromagnet having relatively movable parts, a plurality of closed coils on one of said members to increase the reluctance of the normal flux path during a portion of the relative movement of said members and provide

for deflecting a portion of the flux from such path to thereby curtail the initial pull of the magnet.

10. The combination with a device to be operated, of operating means therefor comprising an alternating current electromagnet having relatively movable parts, a plurality of closed coils on one of said members to increase the reluctance of the normal flux path during a portion of the relative movement of said members and provide for de-

flecting a portion of the flux from such path to thereby curtail the initial pull of the magnet, the arrangement being such that the reluctance of the normal flux path is ¹⁵ gradually decreased during continued relative movement of said members.

In witness whereof, we have hereunto subscribed our names.

WILLIAM C. STEVENS.
ARTHUR SIMON.

CERTIFICATE OF CORRECTION.

Patent No. 1,674,747.

Granted June 26, 1928, to

WILLIAM C. STEVENS ET AL.

It is hereby certified that error appears in the printed specification of the above numbered patent requiring correction as follows: Page 2, line 73, claim 4, for the word "moved" read "movable"; and that the said Letters Patent should be read with this correction therein that the same may conform to the record of the case in the Patent Office.

Signed and sealed this 11th day of December, A. D. 1928.

(Seal)

M. J. Moore,
Acting Commissioner of Patents.
